UNITED STATES PATENT OFFICE.

FERDINAND W. KROGH, OF SAN FRANCISCO, CALIFORNIA; MARY L. KROGH, FANNIE J. CLARKE, C. A. KROGH, AND OSCAR POULSEN, LEGATEES BY COURT ORDER OF DISTRIBUTION OF THE ESTATE OF SAID FERDINAND W. KROGH, DECEASED, AS SIGNORS TO KROGH PUMP AND MACHINERY COMPANY, OF SAN FRANCISCO, CALIFORNIA, A CORPORATION OF CALIFORNIA.

LUBRICATING SYSTEM FOR DEEP-WELL PUMPS.

1,424,362.

Specification of Letters Patent. Patented Aug. 1, 1922.

Application filed May 28, 1918. Serial No. 237,856.

To all whom it may concern:

Be it known that I, FERDINAND W. KROGH, of San Francisco, California, have invented certain new and useful Improvements in 5 Lubricating Systems for Deep-Well Pumps, whereof the following is a specification.

This invention relates to vertical shafts for deep well pumps and other uses, and consists in a lubricating system for such 10 shafts.

In its main feature the invention comprises an oil supply tank from which the oil is fed to the various bearings of the system, either by gravity or other pressure, by 15 means of conducting channels. The oil from the bearings, which exudes therefrom, by leakage or otherwise, is conducted to a waste oil tank, whence it is returned by an oil pump to the supply tank. Suitable fil- 20 tering means are applied to clarify the oil before its final return to the supply. Other features and details of the invention will be set forth hereinafter.

In the accompanying two sheets of drawings I have illustrated the invention, by 25 showing it as applied to deep well centrifugal pump.

Figure 1 is a vertical section of the upper part of such a pump and the well to which 30 it is applied, and

Figure 2 is a similar view of the lower part of the same.

In the figures:—The shaft 1 has thereon the impeller 2, and is driven by the pulley 3 from any suitable power or an electric motor may replace pulley 3. The well is represented by 4 and the pump discharge by 5. Surrounding the shaft 1 is the waste oil tube 6, which receives the oil from the bearings 35 within its sphere of influence and conducts the same to the waste oil tank 7 through the pipe 8 and the chamber 9 at the top of the tube.

The oil supply tank is shown at 10, and is, 40 in the example chosen for illustration, elevated above the highest bearing of the apparatus so that the oil flows thereto by gravity from the tank 10, oil passes through pipe 11 into receptacle 12, which is located at the 45 top of the uppermost bearing 13 of the ap-

paratus. Any overflow from the receptacle 12 passes through the pipe 14 to the tank 7. A stop cock 15 in the pipe 11 controls the flow of oil to receptacle 12. The leakage from the bearing 13 passes down into cup 55 16, which may be made fast to shaft 1. The collected waste oil in cup 16 overflows the edge of said cup and is received in the annular receptacle 17, and passes thence through pipe 18 into tank 7. 19 is a pipe 60 conducting oil from supply tank 10, to the bearing 20, whence the leakage passes partly downward into chamber 9, and thence to tank 7, and partly to the stuffing box 21, whence the overflow is received in the cup 22 65 and passes through pipe 23 to tank 7. A check valve may be applied to pipe 19, as at 24 and a valve may be applied to pipe 8, as at 25. A pipe 26 conducts oil from the supply 70 10 to the lower bearings 27, and below to any desired number, the overflow from 75 which is received in tube 6, as already stated. A force pump may be interposed in pipe 26, as at 28 which will suck from the upper part of the pipe and discharge into the lower 75 part, when it is desired to temporarily increase the pressure of oil upon the bearings supplied by pipe 26.

Oil is returned from tank 7 to tank 10 by pump 29, which draws from tank 7 through 80 pipe 30, and discharges into tank 10 through pipe 31. The pump 29 is driven by bevel pinion 32 and bevel wheel 33, the latter being feathered upon the shaft 1, as indicated, and held in position by the embracing fork 34, 85 connected to the fixed frame, as at 35, whereby the shaft 1 may play up and down without disturbing the engagement of the bevel gearing.

A suitable screen or filter 36 may be in- 90 terposed in tank 7 between the various entering pipes and the out passage pipe 30, whereby the oil is wholly or partially clarified before it is withdrawn from the tank. A similar screen or filter 37 is similarly ap- 95 plied to tank 10 for a similar purpose.

Having thus described my invention, and an embodiment of it, in the full, clear and exact terms required by law, and knowing that it comprises novel, useful and valuable 100

improvements in the art to which it pertains, I here state that I do not wish to be limited to the precise construction and arrangement of the several parts, as herein set forth, as 5 the same may be variously modified by a skilled mechanic without departing from the spirit of the invention.

What I claim and desire to secure by Letters Patent of the United States, is the following, to-wit:—

1. A lubricating system for a vertical shaft bearing of a deep well pump, comprising a supply tank, located above said bearing, means for feeding lubricant from said tank to said bearing, a cup secured to said shaft and rotating therewith, said cup being adapted to receive waste lubricant from said bearing and means connected to said cup for conducting said waste lubricant to said supply tank.

2. A lubricating system for vertical shaft bearings of a deep well pump, comprising a gravity supply tank, means for feeding lubricant from said supply tank to said bearings, a cup secured to said shaft adapted to receive waste lubricant from said bearings, a tank for said waste lubricant, means for connecting said cup to said waste tank and automatic means connected to said waste tank for directing said waste lubricant to said supply tank.

3. A lubricating system for vertical shaft bearings of a deep well pump, comprising a supply tank, means for feeding lubricant from said tank to said bearings, a cup secured to said shaft and rotatable therewith adapted to receive waste lubricant from said bearings, an annular stationary receptacle surrounding said cup for said waste lubricant, a tank adapted to receive said waste lubricant and means for carrying said waste lubricant from said tank to said supply tank.

4. A lubricating system for vertical shaft bearings of a deep well pump, comprising a supply tank, means for feeding lubricant

from said supply tank to said bearings, a cup secured to said shaft for receiving surplus and waste lubricant from said bearings, a waste tank, means for conducting said surplus and waste lubricant from said cup to 50 said waste tank, a pump for directing said lubricant from said waste tank to said supply tank, and means for operating said pump consisting of a pinion connected to said pump and a bevel wheel rotatably mounted upon said shaft engaging said pinion.

5. A lubricating system for a vertical shaft bearing of a deep well pump, comprising a supply tank, means for feeding lubricant to 60 said bearing from said supply tank, a movable cup secured to said shaft and adapted to receive waste lubricant from said bearing, a receiving tank for said lubricant and means connected to said tank operated by 65 said shaft adapted to direct lubricant from said receiving tank to said supply tank.

6. A lubricating system for a vertical shaft bearing of a deep well pump, comprising a supply tank, means for feeding lubricant 70 from said supply tank to said bearing, a movable cup secured to said shaft below said bearing adapted to receive waste lubricant from said bearing, an annular fixed receptacle surrounding said movable cup and projecting below thereof, said receptacle being adapted to receive the waste lubricant from said movable cup, a waste tank connected to said receptacle, provided with filtering means for said lubricant and a pump operated by said shaft and connected to said waste tank adapted to carry back filtered lubricant to said supply tank.

In testimony, that I claim the foregoing I have hereto set my hand this 9 day of May, 85 1918, in the presence of two witnesses.

FERDINAND W. KROGH.
